SAMUEL MATHEW JOHNSON, OF CARDIFF, WALES, ASSIGNOR TO JOHNSON'S
CONVERTIBLE BOATS AND RAFTS LIMITED, OF CARDIFF, WALES.

SHIP'S LIFE OR EMERGENCY BOAT.

1,280,483.

Specification of Letters Patent.

Patented Oct. 1, 1918.

Application filed March 4, 1918. Serial No. 220,207.

To all whom it may concern:

Be it known that I, SAMUEL MATHEW JOHNSON, a subject of the King of Great Britain, and resident of 15 Neville street, 5 Cardiff, in the county of Glamorgan, Principality of Wales, in the United Kingdom of Great Britain and Ireland, have invented a certain new and useful Improvement in Ships' Life or Emergency Boats, of which

10 the following is a specification.

This invention relates to a foldable structure adapted for use alternatively as a ship's life or emergency-boat or as a deck-fitting capable of affording sitting-accommodation 15 for passengers; the object of the invention being to provide a structure which, in its open or unfolded condition, will serve as a pair of back-to-back benches but which can, when necessity arises, be instantly converted 20 into a boat and launched overboard without the use of lowering tackles.

In a practical form, the structure of the present invention comprises a pair of half-boats divided at the median longitudinal 25 vertical plane and connected together permanently at a hinge extending lengthwise of the boat at the keel; these halves, which are provided with locking-devices whereby to secure them together when the structure 30 is folded up, as well as with means for then maintaining a watertight joint between their contiguous surfaces, having each a range of seat-lockers extending lengthwise of what (when the halves are folded together) constitutes the well of the boat, said seat-lockers being adapted to afford bench-accommodation whether the structure be folded up or 35 unfolded.

In the accompanying drawings, which 40 illustrate in a somewhat elementary manner one embodiment of the invention, Figure 1 is a midship cross-section of the structure when folded up and set afloat for use as a boat, Fig. 2 being a similar view showing 45 the structure when unfolded and stowed in-board on the chocks. Fig. 3 is a plan view of the structure when folded up as in Fig. 1, while Fig. 4 is a similar view of the structure when unfolded as in Fig. 2.

50 The halves A and B of the structure, which are substantially similar and are adapted each to constitute one half of the boat, are connected together by means of a hinge *c* which extends throughout their 55 length from the stern to the point *d* (Fig. 4)

whereat the fore-foot of the boat begins to curve upward toward the stem; the hinge *c* which, when the halves A and B are folded together, projects downward beyond the bottom of the boat so as to constitute a keel, 60 being preferably made sufficiently heavy to provide the ballast necessary for rendering the boat self-righting. At *e*, between the keel-hinge *c* and the floor *f* of the well of the boat, and also at the stem *g* and stern *h*, each 65 half A and B is constructed with buoyancy-chambers whereby to render the boat practically unsinkable independently of the use of buoyancy-tanks such as hereinafter described.

The halves A and B are respectively provided, at or near the top of the stem *g* and stern *h*, with mutually-engaging locking-devices *j* adapted, when the halves are folded together as in Figs. 1 and 3, to lock 75 the halves together automatically so as to hold them securely in the relative position required to form a boat; these locking-devices, which are not shown in detail but may be of any convenient construction, being 80 preferably of such character as to prevent disengagement except by an authorized person possessed of a key for the purpose.

In order to render the joint between the halves A and B watertight, a packing strip 85 is interposed between their contiguous surfaces throughout the length of the keel and the height of both stem and stern. For this purpose, in the example illustrated, the inner face of each half has a continuous groove 90 extending lengthwise above the hinge *c* and in an upward direction beyond each locking-device *j*; the grooves in the respective halves being adapted to register with one another and the groove on the one half (B 95 in the drawings) having secured within it a continuous length of thick rubber cork *k* or equivalent compressible or elastic material which, when the halves are folded together, enters and makes joint with the 100 groove *l* on the other half.

In the example illustrated, the meeting faces of the halves A and B are flat and extend in the median vertical longitudinal plane *m* of the boat as indicated in Figs. 1 105 and 3, except that, at the front part of the stem *g*, the one half (A in Fig. 3) overlaps the other half as at *n* so as to provide an undivided and therefore stronger cut-wa-ter *o*.

Each half A and B has fixed against its outer wall, within what (when the halves are folded together) constitutes the well of the boat, a range of lockers *p* of such dimensions as to afford bench-accommodation for passengers on the (for the time being) upper surface of the lockers whether the structure be folded up to form a boat as in Fig. 1, or unfolded as in Fig. 2. In the former case the sides *r* of the boat serve as backs to the benches, whereas in the latter case the halves of the floor *f* of the well serve as backs while the sides *r* serve as foot-boards for persons occupying the seats. 10 When the structure is thus unfolded, the halves A and B are supported in proper

relative position by chocks *s* (Fig. 2) fixed to the deck *t* of the ship.

The lockers *p*, which are preferably provided with sliding doors, may be used to hold oars and other usual fitting, as well as provisions and water. 20

Claim:

A foldable structure comprising a pair of half-boats, a hinge connecting the parts and extending lengthwise at the keel, locking devices for securing the parts together when the structure is folded up, means for maintaining a watertight joint between their contiguous surfaces, and a range of seat-locks 30 extending lengthwise of each part.

SAMUEL MATHEW JOHNSON.
